UNITED STATES PATENT OFFICE.

JOHN AJEMIAN AND KARNIG SHOHLAMIAN, OF SYRACUSE, NEW YORK.

CANOPY FOR COOKING-RANGES.

1,177,080.

Specification of Letters Patent.

Patented Mar. 28, 1916.

Application filed December 1, 1915. Serial No. 64,546.

To all whom it may concern:

Be it known that we, JOHN AJEMIAN and KARNIG SHOHLAMIAN, citizens of the Empire of Turkey, residing at Syracuse, in the 5 county of Onondaga and State of New York, have invented certain new and useful Improvements in Canopies for Cooking-Ranges, of which the following is a specification.

10 This invention relates to improvements in canopies for cooking ranges, stoves, and the like, and has for its object to provide a novel, simple, effective and cheap device of the class for collecting and carrying off the 15 steam, smoke, fumes and odors, arising from the cooking-vessels disposed on the top of such stoves and ranges.

A further object is to provide a novel and simple device of the class for attachment to 20 gas and other cooking ranges, which may be readily and cheaply applied without requiring any alterations or changes in the ranges. And a further object is to provide means for controlling and regulating the 25 draft between the canopy and the main stove pipe.

The various features and parts of the invention will be understood from the detailed description which follows, and by 30 reference to the accompanying drawing, in which—

Figure 1 is a front elevation of the complete device, applied to a cooking stove. Fig. 2 is a central vertical cross-section, 35 taken on line 2—2 of Fig. 1. Fig. 3 is a horizontal section, taken on line 3—3 of Fig. 1. Fig. 4 is a sectional view, showing a plain damper instead of the rotary fan, for controlling the draft between the canopy 40 and the stove pipe.

Similar characters of reference are assigned to corresponding parts throughout the several views.

In the drawing, 2 represents the first joint 45 of the main stove-pipe, which slips over the usual upwardly projecting smoke-vent 3 located at the back of the stove or range 4. The upper end of the joint 2 telescopes the lower end of a second joint 5, to which the 50 back plate 6, which supports the canopy, is secured by rivets 6'.

7 represents the canopy which droops forwardly and laterally, and its apex has an opening 8 through which the joint 5 of the 55 stove-pipe passes, and the canopy may be

held in place by any suitable means, but preferably is supported by its rear edges 9 being secured to the sloping top edges 10 of the back 6, by rivets 11, as shown in Fig. 1. The hollow under-side of the canopy 7, collects or receives the smoke, steam and fumes from the cooking vessels (not shown) on the top of the stove 4. The drooping front 7' of the canopy is perforated at 12, and in this perforation is disposed an auxiliary 65 pipe 13 which extends upwardly along-side and parallel to the joint 5 of the stove-pipe, to which it connects at a perforation 14. The object of the pipe 13 is to conduct the smoke, &c., from the hollow side of the 70 canopy into the main stove pipe, to be carried by the latter to a chimney, along with the smoke and gases thrown off by the fire, by which the stove or range is heated. The pipe 13 at the top-end is preferably formed 75 into an elbow 15, for convenience in attaching it to the joint 5.

16 represents a rotary fan-like damper, which is disposed in the pipe 13, for controlling the draft between the canopy and 80 the stove pipe 5. The damper 16 is mounted on a vertical shaft 17, the opposite ends of which are pointed and these pivot points are received by sockets 18 arranged in cross-pieces or bridges 19, which are supported by 85 the inner sides or walls of the pipe 13, as best seen in Fig. 2. The damper 16 is preferably light, and it is pivoted in such manner that, a slight draft from the chimney or pipe 5 causes it to rotate in the direction 90 for drawing the smoke and steam from the cooking upwardly and forcing it into the pipe 5. The damper also serves to close, to a greater or less extent, the pipe 13, and thus prevents destruction of, or interference 95 with the draft through the pipes 2 and 5, upon which the range depends for its proper firing.

The canopy 7 and back 6 may be made of any suitable material, but we prefer to 100 construct the whole out of sheet iron or steel, of suitable gage and finish to withstand wear and present a neat appearance. When the joints of pipes 2 and 5 are properly made and joined together they will 105 support the canopy without any other securing means.

In Fig. 4, we have shown a common plain disk damper 20, which is disposed in the pipe 13'. This damper is mounted upon a 110

shaft 21, which pierces the pipe diametrically, and is provided at one end with a handle 22 for manipulating the damper.

Our invention is extremely simple, and 5 may be produced at slight expense, and the device may also be readily and quickly applied to any of the cooking ranges or stoves in common use, by any unskilled person, and without requiring alterations or changes in 10 the cooking devices.

Having thus described our invention, what we claim as new and desire to secure by Letters Patent, is—

1. In an attachment for cooking stoves 15 and ranges, a canopy comprising a sheet metal body having forwardly and laterally drooping portions, the apex of said body being perforated, and a back plate for supporting said canopy, in combination with a 20 stove-pipe inserted through the said perforation and secured to and supporting said back plate.

2. The combination with the stove pipe arranged for connection with a cooking

stove or range, of a back supported by one 25 joint of the said pipe, a canopy secured to the top edge of the back, the apex of said canopy being perforated and pierced by said joint of the pipe, and an auxiliary pipe connecting the hollow side of the canopy with 30 the said joint of pipe.

3. The combination with a joint of stove pipe, of a back plate secured to the said pipe, a canopy having an opening in its apex through which the said pipe is inserted, said canopy supported by the top edge of said plate, an auxiliary pipe, the lower end of which pierces the said canopy, its opposite end piercing the said stove pipe 40 for conducting smoke, steam and the odors from cooking vessels from the canopy into the stove pipe, and means for controlling the draft through the auxiliary pipe.

In testimony whereof we affix our signatures.

JOHN AJEMIAN.
